UNITED STATES PATENT OFFICE.

PETER FREDERIC MEYER, OF BROOKLYN, NEW YORK.

PLEASURE-RAILWAY.

1,311,703.

Specification of Letters Patent.

Patented July 29, 1919.

Application filed April 22, 1919. Serial No. 291,858.

To all whom it may concern:

Be it known that I, PETER FREDERIC MEYER, a citizen of the United States, and a resident of the city of New York, borough 5 of Brooklyn, in the county of Kings and State of New York, have invented a new and Improved Pleasure-Railway, of which the following is a full, clear, and exact description.

10 The object of the invention is to provide a new and improved pleasure railway or roller coaster more especially designed for use in pleasure resorts, exhibition grounds, parks and like places, and arranged to provide an exciting and interesting ride for the passengers. Another object is to accommodate safely a large number of passengers in each car. Another object is to prevent a car from jumping or leaving the track.

20 With these and other objects in view, the invention consists of certain novel features of construction, as hereinafter shown and described and then specifically pointed out in the claims.

25 A practical embodiment of the invention is represented in the accompanying drawings forming a part of this specification, in which similar characters of reference indicate corresponding parts in all the views.

30 Figure 1 is a side elevation of the improved pleasure railway with a portion of the track broken out;

Fig. 2 is an enlarged cross section of the same on the line 2—2 of Fig. 1;

35 Fig. 3 is an enlarged sectional side elevation of a portion of the car and track, the section being on the line 3—3 of Fig. 4;

Fig. 4 is a cross section of the same on the line 4—4 of Fig. 3;

40 Fig. 5 is an enlarged sectional plan view of the joint of the members of a ball bearing, the section being on the line 5—5 of Fig. 2;

Fig. 6 is a cross section of the ball bearing;

Fig. 7 is a reduced plan view of a portion of the track;

Fig. 8 is an enlarged cross section of the same on the line 8—8 of Fig. 7 and showing 50 a car in position on the track; and

Fig. 9 is a similar view of the same on the line 9—9 of Fig. 7 and showing a car in position on the track.

The pleasure railway in its general construction comprises a track 10 and a car 11

adapted to travel over the track 10. The track is preferably endless with the beginning portion extending up an incline with means for hauling the car 11 up the incline, to then allow the car to travel down over 60 the remaining track portion by its own gravity, as is common in pleasure railways now generally constructed, it being, however, understood that I do not limit myself to this particular manner of propelling the 65 cars over the track as any other well known means may be employed for the purpose.

The track 10 is made trough-like or semi-circular in cross section, and in the bottom of this track is formed a slot 12, and from 70 the under side of the track at the side walls of the slot 12 extend downwardly parallel walls 13 to provide a guideway 14. This guideway 14 is preferably part way straight, and this straight portion coincides with the 75 median bottom line of the track 10. Other portions of the guideway are made sinuous and extend alternately on opposite sides of the said median line, as plainly illustrated in Fig. 7. The walls 13 rest on a suitable 80 foundation 15 thus forming a support for the track 10 which latter, however, is additionally supported by suitable framework (not shown) if necessary. The car 11 is of a suitable length and the lower portion of 85 the body 20 is semicircular in cross section with side extensions 21 provided with top rails 22. Within the car body is arranged one or a number of seats 23 and the car body is also provided with a suitable floor 24. 90

In order to support the car 11 on the track 10 and to insure easy running of the car on the track, use is made of transverse rows of balls 25 held in bearings 26 of semicircular shape attached exteriorly to the 95 lower semicircular portion of the car body 10. The balls 25 project beyond the outer faces of the bearings 26 and are in rolling contact with the inner surface of the track 10 thus supporting the car on the track and 100 insuring an easy running of the car along the track. Each of the bearings 26 is preferably made in two parts connected together at their lower ends by a pin 27, as plainly shown in Figs. 2 and 5. By reference to Fig. 6 it will be noticed that the side walls of each bearing 26 are contracted at their outer ends 28, and the inner surfaces of the contracted portions 28 are segmental and follow the curvature of the balls 25 to 110

hold the latter in position in the bearings. The inner surface portions of the balls 25 travel on wearing plates 29 screwed or otherwise secured to the bearings, as plainly indicated in Fig. 6. The upper ends of the bearings 26 are provided with suitable oil cups 30 for supplying the bearings 26 and the balls 25 with the desired lubrication. Rails 31 extend lengthwise on the car body 10 on top of the bearings 26 to act as a bumper or guard for the car.

In order to impart a transverse rocking movement to the car 11 while traveling forward on the track 10, the following arrangement is made: To the bottom of the body 20 of the car are secured two or more straps 40 of U-shape and terminating in vertically disposed axles 41 and 42 on which are mounted to turn balls 43 and 44 in rolling contact at their sides with wearing plates 45 and 46 attached to the inner faces of the walls 13 of the guideway 14. It will be noticed that the axles 41 and 42 are disposed on opposite sides of the median line of 25 the guideway 14 and hence one ball 43 is in contact with the wearing plate 45 while the other ball 44 is in contact with the wearing plate 46. By the arrangement described the balls 43 and 44 are carried along by the 30 forwardly moving car and as the said balls are in contact with the wearing plates 45 and 46 of the sinuous guideway 14 it is evident that a transverse rocking movement is given to the car during its forward movement. The balls 43 are engaged at the top 35 and bottom by cup-shaped washers 50, 51 and similar washers 52, 53 engage the top and bottom of the balls 44. The washers 50, 52 are held on a cross-piece 54 held on 40 the axles 41 and 42, and a similar cross-piece 55 is held on the lower ends of the axles 41 and 42 and is supported by nuts 56 screwing on the lower ends of the said axles 41 and 42. Oil cups 57 and 58 are 45 mounted on the top crosspiece 54 and supply oil to the axles 41 and 42 to keep the balls 43 and 44 lubricated. From the bottom of the crossbar 55 depends a lug 60 adapted to be engaged by an arm on a propelling chain 50 for moving the car up the incline at the beginning end of the track to allow the car to travel down the remaining portion of 55 the track by its own gravity.

In order to prevent the car from leaving the track 10 use is made of two guard rails 55 and 71 attached to the wearing plates 45 and 46, above the balls 43 and 44 thus limiting the upward movement of the said balls and consequently limiting any upward movement of the car 11.

Having thus described my invention, I claim as new and desire to secure by Letters Patent:—

1. In a pleasure railway, a trough-like track having a sinuous guideway, and a car

mounted to travel on the said track and having means engaging the said guideway to rock the car transversely during its forward movement.

2. In a pleasure railway, a trough-like track having a sinuous guideway, a car provided exteriorly with balls traveling on the said track, and means on the car engaging the said guideway to rock the car transversely during the forward movement of 75 the car.

3. In a pleasure railway, a trough-like track provided with a sinuous guideway lengthwise of the track, a car provided with balls adapted to travel on the said track, a 80 bracket on the car and extending into the said guideway, and contact means on the bracket engaging the walls of the said guideway.

4. In a pleasure railway, a trough-like 85 track provided with a sinuous guideway extending lengthwise of the track, a car provided exteriorly with spaced transverse rows of balls traveling on the inner surface of the said track, and contact means on the 90 said car engaging the said guideway.

5. In a pleasure railway, a trough-like track provided at its bottom with a depending sinuous guideway, a car provided exteriorly with spaced transverse rows of balls 95 traveling on the said track, and means on the underside of the car and engaging the said guideway to rock the car transversely during the forward travel thereof.

6. In a pleasure railway, a track approximately semicircular in cross section and provided at the bottom with a sinuous slot, the walls of which form a guideway, a car approximately semicircular in cross section and provided exteriorly with a plurality of 105 transverse ball bearings, the balls of which travel on the inner surface of the said track, and spaced posts depending from the under side of the car and provided with walls engaging the walls of the said slot. 110

7. In a pleasure railway, a track approximately semicircular in cross section and provided at the bottom with a sinuous slot, the walls of which form a guideway, a car approximately semicircular in cross section and 115 provided exteriorly with a plurality of transverse ball bearings, the balls of which travel on the inner surface of the said track, spaced posts depending from the under side of the car, each post having two vertical 120 axles arranged on opposite sides of the median line of the slot, and balls journaled on the said axles and engaging the corresponding walls of the said slot.

8. In a pleasure railway, a car having an 125 elongated car body approximately semicircular in cross section, spaced bearings attached exteriorly to the car and extending transversely thereof, and a set of balls held in each of the said bearings and projecting 130

beyond the face thereof to support the car on a track.

9. In a pleasure railway, a track approximately semicircular in cross section and provided at the bottom with a sinuous slot, the walls of which form a guideway, a car approximately semicircular in cross section and provided exteriorly with a plurality of transverse ball bearings, the balls of which 10 travel on the inner surface of the said track, spaced posts depending from the under side of the car and provided with balls engaging the walls of the said slot, and guard rails on the upper ends of the walls of the said

slot above the said balls to prevent the car 15 from jumping the track.

10. A pleasure railway having a track approximately semicircular in cross section and provided at the bottom with a sinuous guide- 20 way.

11. A pleasure railway having a track approximately semicircular in cross section and provided at the bottom with a sinuous slot forming a sinuous guideway extending alternately on opposite sides of the median 25 bottom line of the track.

PETER FREDERIC MEYER.
